United States Patent

Des. 242,384

Patented Nov. 16, 1976

242,384

ORGAN

Thomas E. Kimble, Covington, Ky., assignor to
D. H. Baldwin Company, Cincinnati, Ohio

Filed Nov. 29, 1974, Ser. No. 528,021

Term of patent 14 years

Int. Cl. D17—01

U.S. Cl. D56—2

Fig. 2

Fig. 3

FIG. 1 is a front and left side perspective view of an organ showing my new design;

FIG. 2 is a front elevational view;

FIG. 3 is a right side elevational view; and

FIG. 4 is a fragmentary front, top and left side perspective view.

The rear of the organ is conventional.

I claim:

The ornamental design for an organ, as shown and described.
